PROCESS OF AND APPARATUS FOR REFINING PETROLEUM.

Application filed January 11, 1926. Serial No. 80,502.

Our invention relates to a process of and apparatus for refining petroleum.

It is common practice in the refining of petroleum to vaporize the low boiling point hydrocarbons contained in crude oil or petroleum by heating the crude to a temperature, for instance, of 500° F. and to pass the vapor mixture thus formed through a series of successive cooling dephlegmators, in each of which a vapor having definite end boiling points is condensed and removed. The fractions or cuts so removed each form, when condensed, a commercially marketable product and they usually comprise, in order of diminishing end boiling points, gas oil, stove oil, several grades of distillate, kerosene and gasoline. Dephlegmator plants adapted to operate in this manner are expensive to build and have a relatively small capacity.

20 An object of our invention is to provide a process of and apparatus for refining petroleum which will have a large capacity compared to the initial cost of construction of the apparatus.

25 Another object is to provide a process of refining petroleum which will make possible exact control of the characteristics of the various resulting products.

30 A further object of our invention is to provide a novel fractionating unit for condensing a vapor of definite characteristics from a mixture of hydrocarbon vapors, in which unit the vapor mixture is cooled to a temperature below the higher end boiling point of the products desired, and the particles of liquid thus formed by condensation in the vapor mixture removed therefrom by rapidly rotating the mixture.

35 It is a still further object to provide a novel apparatus for collecting and refining a hydrocarbon liquid which is held suspended in a mixture of hydrocarbon vapors.

40 It is another object to provide a novel combined centrifuge and re-boiler in which the centrifuge places a partial vacuum upon the re-boiler, thereby materially decreasing the boiling temperature of the contents thereof and increasing its heat efficiency.

45 Further objects and advantages will be made manifest in the following description and claims, and in the accompanying drawings, in which—

Fig. 1 is a diagrammatic view of an embodiment of the present invention.

50 Fig. 2 is a vertical sectional view of a con-

densate separator and re-boiler of our invention.

Fig. 3 is a horizontal sectional view taken on the line 3—3 of Fig. 2.

Fig. 4 is a horizontal sectional view taken on the line 4—4 of Fig. 2.

Referring in detail to the drawings, the apparatus shown in Fig. 1 has a crude oil pressure pump 10 which draws crude oil through a pipe 11 from a crude oil storage tank (not shown) and forces it through primary heat exchangers 12, which are connected together in series by means of pipes 13. On leaving the last of the series of primary heat exchangers 12, the crude oil is forced through a pipe 14, heat exchangers 15 and 16, a pipe 17, a water separator 18, and a pipe 19, to a tube still 20. A gas burner 21 in the still 20 provides fire for heating the crude oil passing through the still to a temperature of approximately 500° F. From the still 20 the hot crude oil is led through a pipe 25 to a vaporizer 26. In the vaporizer 26 the lighter hydrocarbons pass off from the crude oil leaving a residuum which is drawn off from the bottom of the vaporizer 26, through a pipe 27, through the heat exchangers 16 and 15, and thence through a pipe 28 to a residuum line 29, which leads to a residuum storage tank (not shown).

35 The mixture of vapors which is given off from the hot crude oil in the vaporizer 26 passes out through the vapor line 30 at the top of the vaporizer and into a centrifuge 31, in which all mechanically entrained liquid is removed from the vapor mixture and drained through the gas trap conduit 33 back into the vaporizer 26. The dry hot vapor mixture then passes from the centrifuge 31 through a vapor line 35 to a standard intercooler 36, which is part of a first fractionating unit 40. The unit 40 comprises the intercooler 36, a condensate separator and re-boiler 43 and a connecting vapor line 46.

40 The intercooler 36 is standard in construction, having a vapor conduit (not shown) which connects at its upper end with the vapor line 35 and at its lower end with a vapor line 46. A jacket 47 surrounds this intercooler vapor conduit and a liquid cooling agent drawn from a storage tank 48 is supplied by a pump 50 through a manifold line 51 and a leader pipe 52 to the bottom of the jacket 47. A liquid return feeder 110

pipe 53 leads from the upper end of the jacket 47 to a return manifold 54, which returns the liquid to the storage tank 48, thus completing the circuit of the liquid cooling agent. A temperature sensitive control valve 56 of standard make is placed in the hot oil return pipe 53 and by shutting off the flow of cooling liquid out from the jacket 47, when the temperature therein falls below a given value, this valve 56 maintains the temperature of the liquid leaving the intercooler 36 by the pipe 53 at that value.

The condensate separator and re-boiler 43 shown in Figs. 2, 3 and 4 has a re-boiler vat 60 having a bottom 61, and sides 62, 63, 64 and 65, which are provided with a continuous flange 66 at their upper edge.

The boiling chamber 68 of the vat 60 is divided by a series of parallel baffle walls 69 into parallel aisles 70. These baffles 69 are secured upon the bottom 61. Every alternate baffle is attached at one end to the wall 62, while the opposite end is spaced from the wall 64 to allow a passage therebetween. The other baffles are attached at one end to the wall 64 and spaced at the opposite end from the wall 62. Thus as the floor 61 is supported in a level position a liquid introduced into the corner 75 of the chamber 68 must flow in series throughout the length of each of the aisles 70 before reaching the corner 76, where a condensate outlet pipe 77 connects through the wall 65 with the chamber 68. A condensate run-down pipe 78 connects to the outlet pipe 77 and leads through a primary crude heat exchanger 12 to a suitable condensate storage tank (not shown).

An intake residuum header box 80 is disposed with a wall 81 thereof parallel and adjacent to the re-boiler wall 62. An outlet residuum header box 82 is disposed with a wall 84 thereof parallel and adjacent to the re-boiler wall 64. Open ended tubes 85 are driven through and rolled snugly into suitably aligned holes in the walls 81, 62, 64 and 84 so that the tubes 85 all communicate between the interiors of the header boxes 80 and 82 and pass through the aisles 70 in batteries of twelve tubes in each aisle. Head plates 86 and 87 close the outer ends of the header boxes 80 and 82 respectively, and have intake and outlet residuum pipes 88 and 89 provided respectively therein.

The intake residuum pipe 88 connects with a hot residuum flow line 90 into which residuum is diverted from the pipe 27. The outlet residuum pipe 89 connects with a cool residuum flow line 92, which connects with the pipe 29 which leads to a suitable residuum storage (not shown).

A series of perforated steam pipes 95 passes through the wall 64, each extending through one of the aisles 70 almost to the wall 62. Each pipe 95 has a valve 96 and connects to a steam manifold 97. The mani-

fold 97 is supplied with steam through a header pipe 98 by a boiler 99.

A re-boiler deck plate 100 rests upon and is secured to the flange 66 so as to completely cover the chamber 68. A conical vapor dome 101 is formed centrally in the plate 100, and has a short vent pipe 102 at the apex thereof.

A cylindrical shell 103 has a flange 104 flaring outwardly from its lower edge, which rests upon and is secured to the deck plate 100 so that the shell 103 will be disposed concentrically about the conical dome 101. At its upper edge the shell 103 is provided with a flange 105 which supports and connects to a flange 106 formed upon the lower edge of a short cylindrical shell 108 of equal diameter to the shell 103.

The shell 108 has an inverted frusto-conical shaped lower extension 110 which projects downwardly into the cylindrical shell 103 below the level of the top of the re-boiler vent 102, where its lower edge 112 is curled inwardly and upwardly to form a condensate trough 113 which has outlet holes 114 formed therein.

A cap plate 116 covers the top of the shell 108 and is secured to a flange 117 formed thereon at its upper edge. The plate 116 cooperates with the shell 108 and its lower extension 110 to form a condensate separating chamber 120. A wet vapor inlet pipe 121 projects tangentially through the shell 108 and opens into the chamber 120, as shown in Fig. 3. A flange 122 on the outer end of the inlet pipe 121 connects to a flange 123 of the vapor line 46, thus joining the latter to the pipe 121.

A vertical dry vapor outlet pipe 125 is coaxially disposed in the chamber 120 and has an open lower end 126 disposed about the re-boiler vent 102 and passes out of the chamber 120 through the cap plate 116. A flange 127 on the upper end of the outlet pipe 125 is secured to a flange 128 formed upon an inter-unit vapor pipe 130, thus connecting the pipe 125 to the pipe 130.

An annular condensate collecting trough 135 is formed between the conical dome 101 and the shell 103. A drain tube 136 connects with the trough 135 through the deck 100 and, as shown in Figs. 2 and 4, leads with a downward slope across the top of the intervening baffle plates 69 to its discharge end 137 which is disposed over the corner 75 of the re-boiler chamber 68.

The fractionating unit 40, as above described, is the first of a series 42 of identical fractionating units. A second unit 141 has an intercooler 142, a vapor connecting line 143 and a condensate separator and re-boiler 144. A third unit 145 has an intercooler 146, a vapor connecting line 147 and a condensate separator and re-boiler 148. The inter-unit vapor line 130 connects to the inlet end of the vapor conduit (not shown) of the inter-

cooler 142. An inter-unit vapor line 149 connects between the vapor outlet of the condensate separator and re-boiler 144 and the vapor inlet of the intercooler 146.

5 While but three fractionating units 40, 141 and 145 are shown as comprising the series 42, it is to be understood that any desired number of units may be utilized in this series.

10 From the vapor outlet of the condensate separator and re-boiler 148, a vapor line 151 leads to a condenser 152 which has a condensate run-down line 153 which leads through a primary heat exchanger 12 to a suitable condensate storage tank (not shown).

15 The fractionating units 141 and 145 have connections to the liquid cooling agent manifold pipes 51 and 54, the residuum manifold pipes 90 and 92, and the steam header 98, identical to those described for 20 the unit 40.

25 Temperature sensitive valves 155 and 156 regulate the amount of cooling liquid leaving the intercoolers 142 and 146 respectively, so as to maintain the temperatures therein at predetermined values. Condensate run-down 30 lines 157 and 158 are adapted to draw off condensate from the re-boilers 144 and 148 respectively, and each passes through a primary heat exchanger 12 to a suitable condensate storage tank (not shown).

The operation of the apparatus above described is as follows:

35 The vapor mixture leaving the vaporizer 26 passes through the centrifuge 31, is dried therein, and then passes down the vapor line 35 to the first intercooler 36. The temperature controlled valve 56 having been set to limit the circulation of liquid through the jacket 47 to maintain a temperature therein 40 below that of the entering vapor, a cooling of the vapor mixture will occur as it passes through the intercooler 36. This cooling will cause the condensing of those vapors in the mixture whose boiling points are some- 45 what higher than the temperature of the intercooler 36. The condensed vapors will form as a mist or finely divided liquid in the vapor mixture.

50 The vapor mixture with this liquid, mechanically entrained therein, passes from the intercooler 36 through the vapor line 46 to the pipe 121, from which it is projected tangentially into the chamber 120. Due to the high speed with which the vapor thus enters the chamber 120 tangentially, it is caused to rotate at high velocity. At the same time the vapor moves downwardly and the decreasing radius of the chamber 120 causes an increase in the rate of rotation of 55 the vapor. This rapid rotation of the vapor mixture throws the liquid condensate entrained therein outwardly against the walls 108 and 110, upon which the condensate collects and runs down into the trough 113. 60 From here the condensate escapes through

the holes 114 to the trough 135, from which it escapes through the drain 136 into the corner 75 of the re-boiler vat 68. When the refining apparatus of our invention is in continuous operation, a depth of condensate 70 which will cover the topmost of the heating tubes 85 is maintained in the re-boiler vat 68. Condensate is drawn off through the outlet pipe 77 at this level at substantially the same rate as it enters the re-boiler at 75 the corner 75, through the pipe 136. As previously described, the baffle plates 69 are so disposed in the re-boiler vat 68 that the condensate entering therein at the corner 75 must pass the whole length of each of the 80 aisles 70 in order to reach the corner 76. And as the condensate covers the pipes 85, all the condensate must come into contact with the pipes 85 in all of the aisles 70. The flow of hot residuum through these pipes 85 85 is regulated so that the condensate will be caused to boil during its passage from the corner 75 to the corner 76.

This boiling will drive off any hydrocarbons in the condensate which are lighter 90 than those desired to be extracted from the vapor mixture in the fractionating unit 40. The vapors thus driven off by boiling rise through the cone 101 and the vent 102 into the mouth 126 of the vapor outlet pipe 125. 95 When the rapidly rotating vapor mixture in the chamber 120 has moved down to the bottom of the conical shell 110, it is deflected upwardly by the turned up edge 112 and enters the open end 126 of the dry vapor outlet pipe 125. The rush of vapor upwardly past the vent tube 102 causes a suction therein, this creating a partial vacuum in the chamber 68 above the boiling condensate. This increases the efficiency of the re-boiler 60 by lowering the boiling point of the condensate therein so as to require less heat to be expended in re-boiling the condensate.

100 In case the dry heat supplied by the residuum pipes 85 is not effective in evaporating all of the lighter vapors, steam may be admitted through the perforated pipes 95 which will lower the partial vapor pressure and complete this vaporization.

105 The vapors driven off by re-boiling are mixed with the main flow of vapor mixture at the upper end of the vent tube 102 and pass with this main flow up the outlet pipe 125 and out therefrom into the inter-unit 110 vapor line 130. This line conducts the remaining vapor mixture to the inlet end of the intercooler 142 of the fractionating unit 141. From here the vapor mixture passes 115 consecutively through the units 141 and 145 in identically the same manner as it passed through the unit 40 and as above described. In these units 141 and 145 the intercoolers 142 and 146 are maintained at temperatures 120 which successively decrease from the temper- 125

ature of the intercooler 36 of the unit 40. Thus in each of the intercoolers in the series of fractionating units 42 the temperature of the vapor mixture will be reduced a given 5 number of degrees below what it was in the preceding fractionating unit. This decrease in temperature is such in each intercooler as to embrace the boiling points of a certain group of the heavier liquids contained as 10 vapors in the uncondensed remainder of the vapor mixture. This cooling will condense these heavier vapors, and when the vapor mixture passes on from the intercooler to the condensate separator and re-boiler of the 15 same unit the condensed vapors will be separated from the vapor, re-boiled and drawn off to storage.

The temperature maintained in the intercooler 146 is such that a few of the lighter 20 hydrocarbons pass out of the condensate separator and re-boiler 148, through the vapor line 151, into the condenser 152, in which they are condensed and pass as a liquid therefrom to storage through the condensate line 153.

The nature of the condensate obtained from each fractionating unit will depend upon the amount which the temperature in 30 its intercooler is lower than the temperature of the last preceding intercooler and the proportionate quantities of the vapors present in the vapor mixture which are condensed by such a drop in temperature.

Thus the succession of temperature drops 35 by which the fractional condensation of the vapor mixture is accomplished may be regulated and the whole series of individual hydrocarbon vapors present in the vapor mixture may be condensed and refined in 40 any desired groups so long as the hydrocarbons of each group are adjacent to each other on the scale of relative boiling points. This power to determine the group of vapors which is to be fractionally condensed and 45 removed from the vapor mixture in each of the fractionating units is made possible by the accurate temperature control of the intercoolers and the novel and efficient condensate separator-and-reboilers of our invention.

Such a regulation of the exact groups of hydrocarbons removed in each fractionating unit gives a control over the products of fractionation which has not previously been 55 had in the petroleum refining industry. This process is particularly valuable inasmuch as it provides a simple means of dividing crude petroleum into products of desired initial and end boiling points and 60 therefore overcomes one of the greatest difficulties in previously known refining practice.

We claim as our invention:

1. A process of refining petroleum comprising: applying heat to the petroleum to 65 drive off hydrocarbon vapors therefrom; cooling the mixture of vapors thus formed to a predetermined temperature; causing said vapor mixture to suddenly expand and rotate at an accelerating speed over a given 70 distance to separate out condensate formed by cooling the vapor mixture; collecting said condensate; and causing said vapor mixture to impose a partial vacuum upon said condensate which communicates with said vapor 75 mixture.

2. A process of refining petroleum comprising: applying heat to the petroleum to drive off hydrocarbon vapors therefrom; 80 cooling the mixture of vapors thus formed to a predetermined temperature; causing said mixture of vapors to rotate rapidly to separate out condensate formed therein by said cooling; collecting said condensate; causing said vapor mixture to impose a partial vacuum upon said condensate; and re-boiling said condensate to drive off lighter 85 hydrocarbons than desired in the product to be formed thereby.

3. An apparatus for refining petroleum comprising: means for vaporizing a number of hydrocarbon liquids from the crude petroleum; means for cooling the vapor mixture thus formed to a predetermined temperature; means for separating out the condensate formed by said cooling by rapidly rotating the vapor mixture; means for re-boiling said condensate; and suction means whereby the vapor mixture surviving the rotary separating means draws a vacuum upon 90 the surface of the condensate in the re-boiling means.

4. In an apparatus for refining petroleum, a condensate collector and re-boiler comprising: a vapor rotating shell of inverted 100 frusto-conical form; means for admitting vapor tangentially into the upper end of said shell; a vapor outlet tube centrally disposed in said shell, the lower end of which is open and is disposed a short distance 105 above the bottom of said shell; a re-boiler having a revaporizing chamber, means being provided for conducting condensate from the bottom of said shell to said re-boiler; a suction tube disposed in the lower mouth 110 of said vapor outlet tube; and a hood conducting vapor from said chamber to said suction tube.

In testimony whereof, we have hereunto set our hands at Los Angeles, California, 115 this 24 day of December, 1925.

FRANK A. MILLIFF.
JOHN A. MILLIFF.
